UNITED STATES PATENT OFFICE.

DANIEL HAYNES AND RICHARD H. HAYNES, OF SEALY, TEXAS.

BAT-FORMING APPARATUS.

1,073,681.

Specification of Letters Patent. Patented Sept. 23, 1913.

Application filed February 21, 1913. Serial No. 749,817.

To all whom it may concern:

Be it known that we, DANIEL HAYNES and RICHARD H. HAYNES, citizens of the United States, residing at Sealy, in the 5 county of Austin and State of Texas, have invented or discovered certain new and useful Improvements in Bat-Forming Apparatus, of which the following is a specification, reference being had therein to the accompanying drawings.

This invention relates to a machine or apparatus for forming bats of fibrous material, the bats being afterward inserted in tickings or coverings to form mattresses; 15 and the invention has for its object to provide an apparatus by which the bat-forming fibrous material may be evenly distributed, and by which the mattress-forming operation may be expeditiously carried on.

20 In carrying the invention into effect a distributing chamber is provided into which the disintegrated fiber, as cotton or the like, will be carried by a blast of air from a cotton gin or other suitable disintegrating machine 25 through a flue extending from the cotton gin to about the middle of the upper part of the distributing chamber, the flue preferably having a downwardly curved discharging end portion terminating above a rocking distributor or baffle plate which is caused to swing slowly back and forth for the purpose 30 of distributing the disintegrated fibrous material as evenly as possible so that it will be deposited uniformly in the receptacle or 35 mold below the distributing chamber. The cotton gin and the distributing chamber adjacent thereto will preferably be located on an upper floor of a building, and through which floor the distributing chamber will 40 preferably be extended down for some distance into the upper part of a lower story of the building. On the floor of this lower story is provided a track or guideway adapted for the reception of a traveling carriage 45 on which will be mounted two molds or bat-forming boxes of dimensions corresponding in cross section to the dimensions of the distributing chamber above, or approximately so, so that the disintegrated fibrous 50 material will fall from the distributing chamber directly into one or the other of the molds or bat-forming boxes. These molds or bat-forming boxes are rotatively mounted on the traveling carriage so that 55 when a bat has been partly formed the mold may be turned half way around to reverse

the positions of the ends thereof, so that if, owing to the conditions of the atmosphere or weather, or to the character of the cotton or other fiber being disintegrated, more of 60 said fiber should be carried to one end of the mold than to the other, a reversal of the ends of the mold will counteract this tendency of the unequal distribution of the fiber endwise of the mold, and will result in the 65 formation of a bat of uniform thickness at both ends.

In the present improved apparatus the molds are provided with hinged sides or doors which may be thrown open when a 70 bat has been completely formed, for the purpose of affording convenient access to the mold in the operation of removing the bat or of placing the same in a cover or ticking for the formation of a mattress. When, 75 therefore, sufficient material has been deposited to form a complete bat the carriage on which the two molds or bat-forming boxes are supported is moved in order to remove the box or mold containing the material for a complete bat to a position 80 convenient for the removal of the bat and to bring the other box or mold mounted on said carriage beneath the distributing chamber, so that the operation of forming another bat may be carried on while the bat first formed is being removed from its box or mold and placed in ticking, or otherwise. Prior to the removal of the bat from its box or mold the loosely laid fiber is compacted 85 or pressed down by means of a follower which can be introduced from above into the mold through the distributing chamber. To this end the distributing chamber is preferably provided at one end with a door 90 which may be opened for the introduction of the follower. Also to permit of the escape of air from the distributing chamber the top or cover of the said chamber is preferably formed of wire cloth through which 95 the air may readily pass without permitting the escape of the disintegrated fiber.

The invention will be understood by reference to the accompanying drawings in which—

105 Figure 1 is a sectional elevation illustrative of the improved apparatus. Fig. 2 is a partial side view thereof. Fig. 3 is a vertical sectional view showing the distributing chamber and its relation to the gin or disintegrating machine. Fig. 4 is a partial plan view of the screen cover of the dis-

tributing chamber. Fig. 5 is a plan view showing the track or guideway and the traveling carriage mounted thereon, and Fig. 6 is a side view of a follower.

Referring to the drawings, 12 denotes the frame or stand of a cotton gin which may be of any well-known form, this cotton gin comprising a driving shaft 13 having a pulley 14 to be rotated by a driving belt extending from any suitable source of power. The cotton gin is located on an upper floor of a building, and adjacent thereto is a distributing chamber 15 into the central part of which extends a flue 16 communicating with the chamber of the cotton gin, and through which flue the disintegrated fiber coming from the gin will be carried by a blast of air created by the rotation of the saws and brushes of the gin, or otherwise. The flue 16 is preferably of a width equal to the width of the mold, or approximately so, and has a downwardly curved end portion 17 terminating above a rocking baffle or distributor 18 which extends from side to side of the distributing chamber 15 and is attached to a bar or shaft 19 extending across the said distributing chamber and through slots 20 in the sides thereof so as to be supported by rockers 21 located outside of the said chamber. A slow rocking movement will be imparted to the rockers 21, for the purpose of carrying the baffle plate or distributor back and forth in the distributing chamber, this movement being preferably effected by a pitman 22 connecting one of said rockers with a rotating crank 23 driven by a large pulley 24 belted to a small pulley 25 on the driving shaft 13 of the cotton gin. By means of the apparatus thus far described the disintegrated fiber will be distributed with great uniformity throughout the chamber 15 so that it may be evenly showered down into a mold or bat-forming box located in the story beneath that in which the cotton gin is located. On the floor 26 of this lower story is provided a track or runway 27 on which is mounted a traveling carriage 28 supporting two molds or bat-forming boxes 29 corresponding in horizontal dimensions to the horizontal dimensions of the distributing chamber 15, and by moving the said carriage in one direction or the other either one of these molds or bat-forming boxes may be brought beneath said distributing chamber. The sides and ends of the bat-forming boxes or molds preferably consist mainly of doors 34 which are hinged at their tops so that they may be raised to afford ready access to a completed bat when the same is to be removed. These doors, when closed, may be secured by any suitable means, as by pivoted latches 35. The bat-forming boxes or molds 29 are preferably pivotally mounted on the carriage 28 by means of king pins or shafts 30 extend-

ing from the bottoms or platforms of the said boxes to plates 31 on the said carriage; or this pivotal connection of the said molds or bat-forming boxes with said carriage may be otherwise effected.

The molds or bat-forming boxes are preferably provided with posts or legs 32 provided at their lower ends with casters 33 which may, if desired, run in circular tracks or guideways on or in the carriage 28, so that the weight of the bat-forming boxes or molds will be sustained by the casters to enable said molds or boxes to be easily rotated, when desired, for the purpose of reversing the ends thereof. This reversal of the ends of the boxes or molds is frequently desirable in order that an even distribution of the disintegrated material may be secured, as it sometimes occurs that, owing to the climatic conditions or the condition of the atmosphere, as also to the character of the material being operated upon, there is a tendency for more of the material to be carried to one end of the distributing chamber than to the other; and under such conditions if it be found that more of the material is being deposited at one end of the bat-forming box or mold than at the other a half rotation of the said box or mold will counteract this uneven distribution of the material and enable the formation of a bat of uniform thickness throughout its length. The walls of the distributing chamber 15 are preferably carried down through the upper floor for some distance into the chamber below, so that the tops of the bat-forming boxes or molds will be closely adjacent to the bottoms of said walls so as to prevent the escape of disintegrated fiber at the joint between the bottoms of the walls of said distributing chamber and the top of a bat-forming box or mold located beneath the same.

The rockers 21 may be held in place in any suitable manner, as by flexible straps 42 attached at their central parts to said rockers and at their ends to the floor by which said rockers are supported.

When a sufficient amount of disintegrated fiber has been deposited in a bat-forming box or mold a door 36, with which the distributing chamber is provided at one end, may be opened and a follower 37 may be introduced into said chamber and lowered into the bat-forming box or mold below. The charged bat-forming box or mold may then, by a suitable traveling movement of the carriage 28, be carried to the position denoted in dotted lines in Fig. 1, and a suitable weight, as a man or otherwise, may be placed on the follower to compress the bat to a condition suitable for its removal. The hinged doors forming the ends and sides of the bat-forming boxes may then be raised and supported from above in any suitable

manner, thus affording unimpeded access to the bat for the purpose of removing the same or placing the same in a cover or ticking to form a mattress. For convenience in lowering the follower a cord or rope 38 attached to or connected with said follower may be passed through an opening in the top 39 of the distributing chamber 15, said opening being provided with a door 40 by which it may be normally closed, and the said follower may be lifted out of the box or mold by passing said rope over a pulley 41 above the box or mold denoted by dotted lines in Fig. 1. The screen top of the distributing chamber is preferably hinged at its end nearest the gin, so that it may be lifted, when desired, for convenience of access to said chamber.

From the foregoing it will be apparent that the present invention provides a convenient bat-forming apparatus by means of which the operation of forming bats for mattresses may be carried on in a practically continuous manner in that a completed bat may be removed from one box or mold and placed in ticking while disintegrated fiber for the formation of another bat is being deposited in the other box or mold. Also the present improved apparatus affords means, in the pivotal mounting of the boxes or molds, whereby an even distribution of the material in the said boxes or molds may, under different atmospheric conditions, and with differing materials, at all times be effected.

The invention is not to be understood as being limited to the details of construction herein shown and described, as these may be varied widely, within the limits of mechanical skill, without departing from the spirit or scope of the invention.

While two bat-forming boxes or molds are herein shown as being mounted on the traveling carriage, it will be understood that a larger number of such bat-forming boxes or molds might be mounted on the carriage by providing a carriage of sufficient length to accommodate more than two bat-forming boxes or molds. So far, however, as concerns the pivotal mounting of the bat-forming boxes or molds it will be understood that this feature might be employed with a single

bat-forming box or mold which might or might not be mounted on a traveling carriage.

55

Having thus described our invention we claim and desire to secure by Letters Patent:

1. In a bat-forming apparatus, the combination with a disintegrating machine, of a distributing chamber, a flue leading from said machine to the central upper part of said chamber where it is provided with a downturned end, a rocking distributer or baffle-plate mounted in said chamber closely adjacent to said downturned end and comprising a curved surface onto which the disintegrated material is discharged, and a bat-forming box or mold into which the disintegrated material is showered from said distributing chamber.

70

2. In a bat-forming apparatus, the combination with a distributing chamber and means for conveying disintegrated material thereto, of a bat-forming box or mold located below said distributing chamber and pivotally mounted so that it may be turned end for end when desired.

75

3. In a bat-forming apparatus, the combination with a distributing chamber and means for conveying disintegrated material thereto, of a rocking distributer in said chamber, and a bat-forming box or mold located below said distributing chamber and pivotally mounted so that it may be turned end for end when desired.

85

4. In a bat-forming apparatus, the combination with a disintegrating machine, of a distributing chamber, a flue leading from said machine to the central upper part of said chamber where it is provided with a downturned end, a rocking distributer or baffle-plate in said chamber and onto which the disintegrated material is discharged, and a pivotally mounted bat-forming box or mold into which the disintegrated material is showered from said distributing chamber.
